UNITED STATES PATENT OFFICE.

ELMER P. NEWMAN, OF DIMONDALE, MICHIGAN.

COPY-BOOK.

SPECIFICATION forming part of Letters Patent No. 235,448, dated December 14, 1880.

Application filed August 10, 1880. (No model.)

To all whom it may concern:

Be it known that I, ELMER P. NEWMAN, of Dimondale, Eaton county, Michigan, have invented a new and Improved Copy-Book, of 5 which the following is a specification.

The object of my invention is to provide a new and improved copy-book which is convenient in use and less expensive than the copy-books in use heretofore.

10 The invention consists in a copy-book having the copies printed in a series of rows on one or more sheets, which rows are separated by perforated lines, so that the copy may be torn off as desired and passed into a suitable copy-holder.

15 In the accompanying drawing my improved copy-book is represented.

The copies A A are printed in rows, preferably arranged transversely on several of 20 the pages C C, preferably the first or last of a writing-book, each row or copy being separated from the next by a perforated line, B, so as to permit of tearing off the copies very easily.

25 The above copy-book is to be used with a copy-holder which permits of moving the copy along the blank pages as the writer progresses. The copies are to be numbered, each copy having the number of its corresponding 30 page in the copy-book.

The great advantage of the within-described copy-book is its cheapness in comparison to all copy-books in use, for at present it is necessary to pass each page of the book into a press to have the copy printed thereon, whereas 35 only the first or last two or three pages of my improved copy need be printed. The copies can also be used for blank-books which are not provided with any copies whatever.

Having thus described my invention, I claim 40 as new and desire to secure by Letters Patent—

1. As an improved article of manufacture, a copy-book made substantially as herein shown and described, with the copies printed 45 in rows on a few pages of the book, each row being separable by perforated lines, as set forth.

2. In a copy-book, the combination, with the blank pages D D, of the pages C C, having a series of perforated rows of copies printed thereon, substantially as herein shown and described, for the purpose set forth.

ELMER P. NEWMAN.
